(57) **CLAIM**

The ornamental design for an audio and docking station for a handheld electronic device, as shown and described.

DESCRIPTION

FIG. 1 is a top plan view of an audio and docking station for a handheld electronic device, embodying my new design;

FIG. 2 is a front elevational view thereof, the rear view being a mirror image thereto;

FIG. 3 is a perspective view thereof;

FIG. 4 is an end elevational view thereof, the opposite end being a mirror image thereto; and,

FIG. 5 is an alternate front elevational view thereof, shown with a handheld electronic device docked thereon.

The broken line showing of the shapes on the top surface and electronic device forms no part of the claimed design.
